SURGICAL CLAMP TOOL

Harold A. Hinckley and Roe C. Hawkins,
Long Beach, Calif.

Application July 15, 1949, Serial No. 104,832

5 Claims. (Cl. 1—49.1)

1

This invention relates to a surgical clamp tool whereby surgical clamps may be quickly and effectively placed by the surgeon to close an incision.

An object of our invention is to provide a novel surgical clamp tool which contains a plurality of surgical clamps and effectively dispenses them one at a time, the tool holding each clamp as it is moved out of the magazine, and then compresses this clamp to close the incision. Heretofore, surgical clamps have been difficult to handle by the surgeon, and required that he pick each one up with a forceps like tool and then carry the clamp to the patient and insert it on each side of the incision. This meant that frequently a clamp would be dropped and at times would fall through the incision, requiring dangerous and additional operative procedure.

A feature of our invention is to provide a novel surgical clamp tool which holds a large number of clamps within the tool, the clamps being dispensed by the downward pressure upon a lever.

Another feature of our invention is to provide a surgical clamp tool which is simple in construction, effective in operation and requires no additional skill in its use.

Other objects, advantages and features of invention may appear from the accompanying drawing, the subjoined detailed description and the appended claims.

In the drawing:

Figure 1 is a longitudinal sectional view of our surgical clamp tool.

Figure 2 is a sectional view taken on line 2—2 of Figure 1.

Figure 3 is a top plan view of a surgical clamp.

Figure 4 is a front elevation of the same.

Figure 5 is a fragmentary sectional view taken on line 5—5 of Figure 1.

Referring more particularly to the drawing, our surgical clamp tool is adapted to hold, dispense and compress surgical clamps 1, which consists of a band of metal formed with a loop 2 on each end, and with a barb 3 on each end and on the bottom, the barb being forced into the skin, and when the clamp is pressed together, these barbs bite into the skin and serve to close the incision. The natural stiffness of the metal will serve to hold the incision closed. The construction of the clamp is usual and well known in the medical profession.

Our tool consists of a barrel or magazine 4 in which a rail 5 is provided, upon which the clamps 1 are racked. The rail 5 is preferably fixedly mounted in the wall of the magazine 4 and extends longitudinally of this magazine. A rider 6

2

on the rail is urged forwardly by the spring 7, surrounding the rail 5, and this rider engages the innermost clamp, and thus presses all of the clamps towards the outer or discharge end of the tool.

A head 8 is formed on the outer end of the magazine 4 and this head is provided with a longitudinal opening 9. A lever 10 is pivotally mounted on the rear end of the magazine 4 as shown at 11. A pair of fingers 12—13 are pivotally attached to the forward end of the lever 10, and this pivot is sufficiently loose to permit inward movement of the fingers. Each of the fingers is provided with a hook 14 at its lower end, which fits the ring 2 and serves to grasp and hold the clamp as it is moved out of the magazine 4 on downward movement of the lever 10.

Within the opening 9 a pair of cams 15—16 are formed which are engaged by the shank of the fingers 12—13, thus pressing these fingers inwardly to cause the hooks 14 to engage and hold the rings 2 of the clamps 1. The cams 15—16 are preferably integrally formed with the head 8 and project inwardly from the wall of the said head. Thus, as the lever 10 is moved downwardly, the clamp 1 is first securely grasped by the hooks 14; the surgeon then places the barbs 3 on each side of the incision and then on further downward movement of the lever 10, the curved portion 17 of each of the fingers 12 and 13 enters the opening 9, and causes the fingers 12 and 13 to move inwardly a further amount, thus compressing the clamp 1 and closing the incision, as well as the bending of this clamp so that the incision will be held in a closed position.

A door 18 is horizontally mounted on the bottom of the magazine 4. A hinge 19 is at the rear of the magazine and the forward end of this door snaps into the head 8, that is, the head is recessed to receive the forward end of the door with a snap or pressure fit. To rack the clamps, it is only necessary to swing the door 18 downwardly and then hold the rider 6 back against the tension of the spring 7, and then the clamps can be slid on to the rail 5, one at a time, until the rail is completely filled. This rail terminates just short of the opening 9 in the head 8 and the clamp about to be ejected is held into position by the pressure of the spring 7 against the adjacent clamps which are racked on the rail 5.

In use, the surgeon picks up the tool loaded with clamps and places one clamp after another by merely depressing the lever 10. This can be done with one hand and can be quickly and easily accomplished without danger of dropping or losing a clamp, and further, without having

to reach some distance in order to pick up one clamp at a time. If desired, the head 8 of the tool may be arranged at an angle to the magazine 4, thus making it easier for the surgeon to use the tool, and still place the bottom of the head flat against the patient.

Having described our invention, we claim:

1. A surgical clamp tool comprising an elongated magazine, said magazine being adapted and arranged to receive a plurality of clamps placed side by side, ejecting means adapted to engage and eject said clamps one at a time, said ejecting means comprising a pair of fingers positioned at one end of the magazine, manually operable means mounting said fingers for reciprocal movement over the end of the magazine, means engageable by the fingers to urge said fingers inwardly to grasp a clamp as said fingers are moved over the end of the magazine.
2. A surgical clamp tool comprising an elongated magazine, said magazine being adapted and arranged to receive a plurality of clamps placed side by side, ejecting means adapted to engage and eject said clamps one at a time, said ejecting means comprising a pair of fingers positioned at one end of the magazine, manually operable means mounting said fingers for reciprocal movement over the end of the magazine, a cam means engageable by the fingers to urge said fingers inwardly to grasp a clamp as said fingers are moved over the end of the magazine.
3. A surgical clamp tool comprising an elongated magazine, said magazine being adapted and arranged to receive a plurality of clamps placed side by side, ejecting means adapted to engage and eject said clamps one at a time, said ejecting means comprising a pair of fingers positioned at one end of the magazine, manually operable means mounting said fingers for reciprocal movement over the end of the magazine, means engageable by the fingers to urge said fingers inwardly to grasp a clamp as said fingers are moved over the end of the magazine, and a curved claw formed on the lower end of each of said fingers, said claw engaging the side of the clamps to hold the same and to move said clamps into a final advanced position.

4. A surgical clamp tool comprising an elongated magazine, said magazine being adapted and arranged to receive a plurality of clamps placed side by side, ejecting means adapted to engage and eject said clamps one at a time, said ejecting means comprising a pair of fingers positioned at one end of the magazine, a head at the end of said magazine in which said fingers are mounted, manually operable means mounted on the magazine, means securing said fingers to said manually operable means, a cam in said head engageable by each of the fingers to urge the fingers inwardly to grasp a clamp as the fingers are depressed.

- 15 5. A surgical clamp tool comprising an elongated magazine, said magazine being adapted and arranged to receive a plurality of clamps placed side by side, ejecting means adapted to engage and eject said clamps one at a time, said ejecting means comprising a pair of fingers positioned at one end of the magazine, a head at the end of said magazine in which said fingers are mounted, manually operable means mounted on the magazine, means securing said fingers to said manually operable means, a cam in said head engageable by each of the fingers to urge the fingers inwardly to grasp a clamp as the fingers are depressed, and a cam on each of the fingers, said latter cams being engageable with the head whereby the fingers are pressed inwardly to compress the clamp on downward movement of said fingers.
